UNITED STATES PATENT OFFICE.

WILLIAM KELLY, OF DETROIT, MICHIGAN, ASSIGNOR TO MAXWELL MOTOR COMPANY,
INCORPORATED, OF DETROIT, MICHIGAN.

GAS-ENGINE.

1,140,163.

Specification of Letters Patent. Patented May 18, 1915.

Application filed February 28, 1910. Serial No. 546,295.

To all whom it may concern:

Be it known that I, WILLIAM KELLY, a citizen of the United States, residing at Detroit, county of Wayne, State of Michigan, have invented a certain new and useful Improvement in Gas-Engines, and declare the following to be a full, clear, and exact description of the same, such as will enable others skilled in the art to which it pertains to make and use the same, reference being had to the accompanying drawings, which form a part of this specification.

My invention relates to gas engines and an object of my improvements is to provide an improved gas engine and one having a compact and convenient arrangement of parts. I secure this object in the device illustrated in the accompanying drawings showing a multi-cylinder gas engine embodying my invention.

Figure 1, is a section on line 1—1, Figs. 3 and 6. Fig. 2, is a section on the line 2—2, Figs. 3 and 6, showing only the upper part of the crank case. Fig. 3, is a side elevation of a multi-cylinder gas engine embodying my invention. Fig. 4, is a detail section on the line indicated by 4—4, Fig. 1. Fig. 5, is a detail sectional plan view on the line indicated by 5—5, Figs. 2 and 3. Fig. 6, is a plan view of the engine casing, the cover of the water-jacket being removed and closures for the passages opening to the valves also being removed. Fig. 7, is an inverted plan view of the casing, the lower part of the crank case being removed.

A¹, A², A³, A⁴ are cylinders cast integral with each other and with the crank case B and water jacket A. The water jacket is open at the top, as indicated most distinctly in Fig. 6, except when closed by screwing thereon a cover a.

b is a detachable lower portion of the crank case B. The portion b may be removed to permit access to the interior of the crank case and working parts, as indicated in Fig. 7.

S is the main shaft of the engine and F is the fly-wheel thereon.

E is a casing cast integral with the water-jacket A and forming a manifold into which the exhaust passages from all the cylinders open.

e is an exhaust pipe leading from the end of the manifold E.

55 I is a casing cast integral with the water-

jacket A and with the manifold E and forming a manifold with which the intake passages of all the cylinders communicate. There is an opening I⁵ (Fig. 5) in the lower wall of the manifold I with which an intake pipe i communicates. There is a greater space between the two central cylinders than between the others and the intake pipe i passes between said cylinders and communicates with the manifold I, as shown in Figs. 1, 2, and 3.

E¹, E², E³, E⁴ are exhaust valves, the passages which they govern opening directly into the manifold E, as indicated in Figs. 2 and 4.

I¹, I², I³, I⁴ are intake valves, the passages which they govern opening directly into the manifold I, as indicated in Figs. 1 and 4. There is a common wall between the manifolds E and I.

e¹, e², e³, e⁴ are the valve rods governing the exhaust valves. The outer exhaust rods e¹, e⁴ are outside of the manifold I and the inner exhaust rods e², e³ pass through openings in a solid portion N (Fig. 5) which projects from the inner wall of the manifold I.

It will be observed that by the above construction a neat and compact arrangement of the intake and exhaust passages is secured, that the charge passing into the cylinders passes through the manifold I, which is adjacent to, and is heated by, the exhaust gases in the manifold E, so that condensation will not take place in the intake manifold and the mixture will be more uniform and complete. The manifolds being cast upon the water-jacket are thereby prevented from undue heating while the exhaust supplies heat to the intake gases.

Claims:

1. In an explosion engine, a plurality of cylinders, an exhaust and intake manifold cast integral and upon one side of the cylinders, one of said manifolds being located above the other, a row of exhaust and intake ports located side by side upon said side of said cylinders, in one plane, passages leading from said exhaust ports to said exhaust manifold, and passages leading from said intake port to said intake manifold, valves controlling said ports, and a single cam shaft adapted to actuate said valves.

2. In an explosion engine, a plurality of cylinders, an exhaust and intake manifold

cast integral and upon one side of the cylinders, one of said manifolds being located above the other, a row of exhaust and intake ports located side by side upon said side of said cylinders, in one plane, passages leading from said exhaust ports to said exhaust manifold, and passages leading from said intake port to said intake manifold, valves controlling said ports, and a single cam shaft adapted to actuate said valves, valve stems extending vertically between said

valves and said cam shaft, a part of said valve stems being located outside of the lower manifold and a part extending through a solid portion of the casting filling 15 said lower manifold adjacent to said stems.

In testimony whereof, I sign this specification in the presence of two witnesses.

WILLIAM KELLY.
